ATTORNEY.

UNITED STATES PATENT OFFICE.

STILLMAN W. ROBINSON, OF COLUMBUS, OHIO.

SUBSTRUCTURE FOR ELEVATED RAILWAYS.

SPECIFICATION forming part of Letters Patent No. 404,017, dated May 28, 1889.

Application filed July 23, 1888. Serial No. 280,829. (No model.)

To all whom it may concern:

Be it known that I, STILLMAN W. ROBINSON, a citizen of the United States, residing at Columbus, in the county of Franklin and State of Ohio, have invented a certain new and useful Improvement in Substructures for Elevated Railways, of which the following is a specification.

My invention relates to that class of sub-
10 structure wherein elevated railways are sup-
ported upon vertical metallic columns, the
latter being anchored to a substructure lo-
cated beneath or partially beneath the sur-
face of the street.

15 The objects of my invention are to provide
a substantial support for superstructure; to
so form and construct the same as to obviate
the necessity of using masonry; to accom-
plish these objects with the necessity of but
20 slight if any excavation, and to construct
and erect my substructure in a speedy, accu-
rate, and substantial manner without causing
unnecessary obstruction of the streets during
the construction of the elevated railway.
25 These objects I accomplish in the manner
illustrated in the accompanying drawings, in
which—

Figure 1 is an elevation of the column-sup-
porting parts, the line of street-surface being
30 indicated by line *v v*. Fig. 2 is a central ver-
tical section of the same, taken on line *x x* of
Fig. 3. Fig. 3 is a transverse section taken
on line *z z* of Fig. 1. Fig. 4 is a view of one
35 of the pile-caps inverted and showing the pile
in cross-section connected therewith. Fig. 5
is a side elevation of the upper portion of one
of the piles, showing a modified form of cap
connected therewith. Fig. 6 is an under side
view of the cap and pile-section shown in
40 Fig. 5. Fig. 7 is an under side view of the
pile-cap, showing a different manner of an-
choring the supporting-column base-plate to
the pile; and Fig. 8 is a vertical section of
the same, taken on line *y y* of Fig. 7.
45 Similar letters refer to similar parts
throughout the several views.

A represents the piling, consisting, as
shown, of four metallic piles of the class
known as "flange piles." These piles A are
50 driven into the earth in the usual manner
until below the surface of the street, each pile
being preferably located at one of the corners

of an imaginary square. Upon the head or
upper end of each of these piles is placed a
metallic plate, B, having formed therewith a 55
downwardly-extending lip or flange, *b*, to
which is riveted or otherwise secured two of
the flanges *a* of the piles A, as shown in
Fig. 4. Seated upon the upper sides of the
pile plates or caps B, and rigidly secured 60
thereto by means of bolts or rivets, is a me-
tallic base-plate, C.

Made to extend upwardly from the upper
surface of the base-plate C, to which they are
secured, as hereinafter described, are two 65
metallic plates, D, each of said plates D being
bent from an imaginary vertical line drawn
on each side of the center of its width to form
two outwardly-extending and diverging
wings, *d*. These approximately V-shaped 70
plates, thus formed, are so placed that their
central portions, or portions between the
wings *d*, will be parallel with each other and
with two opposite sides of the plate C, the
lower edge of said central portions being 75
made to rest respectively on opposite sides of
the center of the base-plate and their outer
edges terminating respectively at or near the
corners of said base-plate.

The central portion of each of the plates D 80
may be continued upward to form a neck, *d'*.
E represent angle-bars bent to conform to
the bend of the plates *d*. The outwardly-ex-
tending and diverging arms *e* of these angle-
bars E are made to bear within the angle 85
formed by the union of the lower edges of
the plates D and the base-plate C, the lower
flanges of said arms being riveted to the said
base-plate, and their upper flanges being like-
wise secured respectively to the outer sides 90
of the wings *d* of the plates D, thus assuring
the latter in their above-described position.
The upper corners of each of the plates D are
preferably clipped to slope from the central
column, hereinafter described. Riveted or 95
otherwise secured to each of the plates D, ad-
joining its outer edge and crossing said plate
at the base of the neck *d'*, is one flange of an
angle-bar, *f*.

G G represent vertical channel-bars, which 100
extend upward from the upper side of the
base-plate between the inner sides of the cen-
tral portions of the plates D; their outer
sides being parallel with and a short distance

from the central portion of the upwardly-extending flange of the angle-bar E. These channel-bars G have their flanges turned inward and secured by rivets or otherwise to 5 the inner sides of the plates D, and are continued upward to form the main body of the column supporting the superstructure. The channel-bars G are connected, as shown, by slats or lacing H.

10 *i i* represent vertical strengthening-plates, one or more of which may be riveted to the outer sides of the channel-bars, and also secured at their lower ends between said channel-bars and the angle-bars E.

15 The superstructure may be attached to and supported on the upper ends of the columns thus formed, in the usual manner.

In anchoring the base-plate to the pile, instead of the construction shown in Fig. 4 and 20 above described, a strap-bolt, *m*, may be used, as shown in Figs. 7 and 8, the strap end of which is riveted or bolted to the web of the pile, with the bolt end projecting through a hole in the cap and base-plate, said bolt end 25 having a nut, *m'*, thereon adapted to be made to bear against the upper side of the base-plate.

In Fig. 5 is shown a construction of cap better adapted for wrought-iron, consisting of 30 two angle-plates, *n n'*, one lying upon the other, between the angle-flanges of which is riveted or bolted the pile A, as shown.

It is obvious that the particular form of parts herein shown and described, the num-

ber of piles mentioned, and the details of 35 construction herein shown, may be changed without preventing the attainment of the objects of my invention or altering its principle.

It will be seen by the above-described construction that a substantial form of sub- 40 structure is provided, the use of which will obviate the necessity of using masonry and forming excavations, thus admitting of a rapid construction, with but comparatively slight inconvenience to or interruption of 45 street-traffic.

Having now fully described my invention, what I claim, and desire to secure by Letters Patent, is—

1. In a substructure for elevated railways, 50 the combination, with three or more piles having caps *b*, of a base-plate secured to caps and piles and a superstructure-supporting column supported on said base-plate, substantially as and for the purpose specified. 55

2. The combination, with three or more piles, A, having flanged caps *b*, to which they are secured, of base-plate C, secured upon said caps, a superstructure-supporting column supported upon said base-plate and 60 plates D, and angle-bars secured to said base-plate and column, substantially as and for the purpose specified.

STILLMAN W. ROBINSON.

In presence of—

C. W. ALLISON,
C. C. SHEPHERD.
